United States Patent Office

Des. 212,565

Patented Oct. 29, 1968

212,565

POWERED AQUATIC VEHICLE

Clayton J. Jacobson, 5403 Seacrest Drive,
Rolling Hills, Calif. 90274

Filed Sept. 11, 1967, Ser. No. 8,539

Term of patent 14 years

(Cl. D71—1)

FIG.1

FIG.2

FIG.3

FIG.4

FIG.5

FIG.6

FIGURE 1 is a perspective view of my new and ornamental design for a powered aquatic vehicle;

FIGURE 2 is a top plan view of the vehicle;

FIGURE 3 is a side elevational view;

FIGURE 4 is a rear elevational view of the vehicle;

FIGURE 5 is a front elevational view of the vehicle design; and

FIGURE 6 is a rear elevational view thereof showing the movable stabilizers in a vertical position adjacent the body.

I claim:

The ornamental design for a powered aquatic vehicle, as shown and described.
